US0D1055540S

(12) United States Design Patent (10) Patent No.: US D1,055,540 S
(45) Date of Patent: * Dec. 31, 2024

(54) LOVE SEAT

(71) Applicant: Jingning Meige Technology Service Co., Ltd., Zhejiang (CN)

(72) Inventor: Yinuo Shen, Zhejiang (CN)

(73) Assignee: Jingning Meige Technology Service Co., Ltd., Zhejiang (CN)

() Term: 15 Years

(21) Appl. No.: 29/954,359

(22) Filed: Jul. 26, 2024

(51) LOC (14) Cl. 06-05

(52) U.S. Cl.

USPC D6/335; D6/336; D6/381
